UNITED STATES PATENT OFFICE.

ORVILLE HIRAM ENSIGN, OF PASADENA, CALIFORNIA.

CARBURETER.

1,223,159.

Specification of Letters Patent. Patented Apr. 17, 1917.

Application filed November 21, 1912. Serial No. 732,746.

To all whom it may concern:

Be it known that I, ORVILLE H. ENSIGN, a citizen of the United States, residing at Pasadena, in the county of Los Angeles and 5 State of California, have invented new and useful Improvements in Carbureters, of which the following is a specification.

This invention is an improvement upon the carbureters heretofore invented by me 10 and described in my applications filed in the United States Patent Office, as follows:

Serial No. 669672, filed January 5, 1912;

Patent No. 1,064,627, June 10, 1913; and

Serial No. 690191, filed April 11, 1912; 15 Patent No. 1,064,628, June 10, 1913 and the carbureter invented by Roy Francis Ensign, filed in the United States Patent Office May 23, 1912, Serial No. 699348, Patent No. 1,108,727, Aug. 25, 1914 and which carbureters are common to each other in that a 20 vortex is depended upon to proportion and effect the mixture.

An object of the present invention is to permit internal combustion engines supplied 25 by this carbureter to run at extreme slow speed and to avoid stoppage heretofore reliable to occur upon sudden slowing down when the mixture from the carbureter is drawn upward toward the engine.

Another object is to permit of adjustment 30 of the mixture of liquid fuel and air for the purpose of using a strong mixture while the engine and air are cold and adjusting it to a weaker mixture when the engine and air supply are heated so that heavy hydrocarbon fuels may be successfully used.

Another object of the invention is to admit of greater flexibility in the adaptation 35 of the carbureter to various types of engines by making the vortex mixing chamber in such a form that the inlet air nozzle may be set at any angle with reference to the other portions of the carbureter.

The accompanying drawings illustrate the 40 invention.

Figure 1 is an elevation partly in vertical axial section of a carbureter constructed in accordance with this invention.

Fig. 2 is a horizontal section on line $\alpha\alpha$, 45 Fig. 1.

Fig. 3 is a view analogous to Fig. 1 showing the mixture adjusting appliance that is not required with the lighter hydrocarbon or carbohydrate fuels.

Fig. 4 is a horizontal section on line $\beta\beta$, 50 Fig. 1.

The supply means comprise the liquid supply chamber 1 having a circular contour excepting that the usual valve chamber 2 projects from one side; said liquid supply chamber being covered by a circular cap 3 having a central perforation 4 through which the upper end of a chambered bolt section 5 of the connecting bolt extends. The bottom of the chamber 1 is provided 35 with a centrally threaded orifice 6 to receive the screw-threaded upper tubular end of the connecting bolt section that forms the stem 7 of a hollow conical distributor 8; said stem being screwed through said orifice 6. 70 Onto the top of the stem 7 is screwed the lower chambered portion 9 of said bolt section 5.

The vortex mixing or carbureting chamber is formed by the hollow snail shell-like 75 body 10, which is of general circular contour, provided with a tangential hollow branch 11 fitted with a contracted vein nozzle 12, which is screwed onto the branch 11, thus forming the air inlet into the carbureting chamber. The top and bottom of the walls of the carbureting chamber 10 are provided respectively with circular seats 13 and 14 fitting respectively, the bottom of the supply chamber 1 and the top of the 80 outlet passage member 15, which is preferably formed integral with a bell-like cup 16 that constitutes the bottom of the carbureting chamber, having a central outlet orifice 17 directly below and overhanging by the 85 hollow conical distributor 8.

The margin of the outlet orifice 17 is in the form of a lip 18, the diameter of which is less than that of the annular edge of the conical distributor 8, which annular edge is 90 sharp to cause liquid leaving the distributor to be torn into fine particles.

The connecting bolt terminates at its lower end in a solid portion 19 screw-threaded at its lower end and extending through a hole 100 20 in the bottom of the outlet member 15 and there threaded and fitted with a nut 21 to engage the bottom of the outlet member 15, thus to clamp said member, the vortex chamber 10 and the supply chamber 1 105 tightly together, but allowing relative rotation of the several parts whenever the thumb nut 21 is loosened so that various angular adjustment of the parts can be effected.

The upper portion of the stem 7 is provided with a nozzle 22, the bore of which extends down to the top of the vortex car-

bureting chamber and opens thereinto through the horizontal hole 23. Said nozzle 22 extends into the nozzle chamber 24 formed by the enlargement of the lower end of the hollow connecting bolt section 5, and its external diameter is less than the internal diameter of the chamber 24 thus forming an annular passage *a* between the nozzle and the chamber walls, and said annular passage 10 communicates with the interior of the supply chamber below the liquid level thereof through one or more orifices 25 so that liquid may flow from the supply chamber into said passage and up and over into the 15 bore 22 and thence downward and through the horizontal hole 23 into the carbureting chamber above the top of the distributor 8. The outlet member 15 is shown as formed in a horizontal and a vertical limb and at the 20 bend between said limbs is provided with a sump 26; the upper portion of said passage being formed by the nipple 27 and throttle body 28 and provided above said sump 26 with a throttle valve 29 controlled in the 25 usual way.

The liquid transfer tube 30 having its lower end near the bottom of the sump 26 communicates between said sump and the outlet passage beyond the throttle valve. 30 The sump 26 is provided with a minute overflow orifice 31 about on a level with the bottom of the inside of the horizontal limb of the outlet member 15.

The hydrocarbon liquid 32 to be vaporized 35 is maintained at a determined level in the liquid supply chamber by the usual float valve means including the float 33, lever 34 and valve 35 and normally seals the nozzle chamber from the air in the liquid supply 40 chamber.

In the form shown in Fig. 3 the nozzle chamber 24 communicates with the liquid in the supply chamber through the orifices 25 and with the air in the mixing chamber 45 through the bore 22 and hole 23 and is provided with a passage 36 leading to the atmospheric air through the hollow wing nut 37 that is provided with an upper interiorly threaded hollow portion 38 through which 50 is screwed a threaded valve stem 39, the valve tip 40 of which is adapted to more or less fully close the mouth of the passage 36; there being, however, a nick 41 in said mouth to prevent the valve from absolutely 55 closing the orifice.

The operation of this carbureter is as follows:

When the engine attached to the throttle body 28 is started, suction is produced 60 through the carbureter and a resulting vertical action is set up in the carbureting chamber and a mixture of the liquid fuel and air is formed by such action.

At the bottom of the vortex chamber a 65 low pressure zone is created which causes

air to flow into the nozzle 12. The velocity of the inflowing air causes it to rotate at a high rate of speed about the distributor 8, causing an induced low pressure zone around the stem of the distributor and at the hole 70 23. This drop in pressure is communicated through the bore 22 to the nozzle chamber 24.

Such lowering of the pressure causes the liquid to flow through the orifice 25 and 75 through the chamber 24 over the top and down from the bore 22.

The orifice at 25 is made larger than is necessary to give a perfect combustible mixture when the engine and air supplied to the carbureter are warm because the heavier hydrocarbons will explode with air easier when cold if the mixture is strong in fuel. After the engine has run a while, the mixture is weakened to produce a proper mixture which will give maximum results. This is done by opening the passage 36 by means of the valve 40 thus weakening the suction on the orifice 25.

The nick 37 is provided to prevent any 90 possibility of siphoning of the fuel after it has been started. The valve 40 thence becomes a medium for adjusting the mixture.

This form of carbureter needs no adjustment except, for the purpose above mentioned, viz., to provide for a strong mixture while warming up the engine, when using heavy hydrocarbon fuels, such as benzine, benzole, kerosene and other low gravity hydrocarbon distillates, and therefore the form 95 100 shown in Figs. 1 and 2 will usually be preferred.

The tube 30 is provided to make it possible to operate the engine at very slow speeds, and the operation in this particular 105 is as follows:

Should the engine be operating at full speed and power, and the throttle be suddenly closed, the momentum of the inflowing air being thus checked, increases for an instant the pressure within the vortex chamber so that it would reverse the flow of fuel momentarily through the orifice 25 and cause the deposit or condensation of the fuel suspended in the air of the vortex chamber, the outlet passage and the nipple 27. The liquid of condensation dropping to the bottom of the horizontal limb of the outlet passage accumulates in the sump 26 and is immediately drawn through the tube 30 110 around the throttle and to a point thereabove where it is again mixed with and enriches the mixture which is being drawn through the throttle, said mixture having been weakened by said condensation. As the throttle 115 120 is nearer to the engine and is generally connected to parts that are warm, no difficulty is encountered in transporting this mixture on from this point and exploding it. Before this condensed fuel has all been exhausted 125 130

from the sump, normal operation of the carbureter through the vortex chamber has been resumed at very much reduced capacity and the fuel is drawn through the orifice 25 and thus into the vortex chamber in the proper proportion but still due to the slow velocity of the flowing air it is not all sustained as a mixture under the throttled slow speed running of the engine and a portion of said liquid condenses from out of the air stream and flows into the sump 26 and is instantly drawn above the throttle as before described. At the mentioned slow speed, it is understood that the throttle is always slightly open.

It is thus seen that by the use of this tube, the mixture proportioning function of the carbureter continues at slow speed and the proper mixture is maintained above the throttle in spite of the tendencies to drop the fuel. This prevents the phenomena commonly referred to by automobile experts as loading-up or the filling of the carbureter passages with a surplus of condensed vapors which usually, upon the opening of the throttle after a period of slow running, causes a too rich mixture for an instant and stops the engine because such mixture will not ignite under the conditions then controlling.

When the air tube 36 is open as shown in Fig. 3 and the carbureter in operation a flowing column of air is drawn through the tube 22 and said air passes thence through 35 23 into the mixing chamber 10. Liquid flowing from the supply chamber 32 is applied externally to said flowing column of air. This gives an additional advantage in more thorough mixing by applying an external skin of liquid fuel to the flowing column of air which expands inside the carbureting chamber thus initially introducing to the center of the carbureting chamber, a fine mist of the liquid which is there expanded and thoroughly mixed with the air whirling around within said chamber. Operating an engine by a more perfect mixture results not only in economy of fuel, but also in reduced cylinder-heating because combustion is not so nearly continuous as it is where the initial combination of oxygen and carbon is less intimate.

It is important in the type of carbureter described in this specification that the fuel supply means shall consist of a float bowl and adjustments arranged above the carbureting chamber for the reason that at slow speeds of the motor under throttling conditions when idling or developing a small amount of power at slow speed, the suction produced by the vortex carbureting chamber is very light, varying with different motors from $\frac{1}{8}$ th of an inch up to a probable maximum of $\frac{3}{8}$ ths of an inch of water pressure. Were an attempt made to

reverse the arrangement of fuel chamber and vortex chamber, it is practically a mechanical impossibility to lift up the fuel from the fuel chamber into the carbureting chamber at such low suction pressure. 70 When operating at the low idling speeds the low vortex suction in this carbureter only acts to pump the fuel over from the fuel chamber into the carbureting chamber, and the mixing is necessarily not accomplished here at these speeds because of the low velocity of air through the carbureting chamber. The supplied liquid fuel then flows by gravity down the outside of the cone and a portion of such supplied fuel 80 finally reaches the bottom of the fuel outlet member 15 and flows to the sump 16 where it is picked up by the tube 30 under the high vacuum existing above the closed throttle; and the liquid fuel is delivered 85 through the tube 30 into the space above the butterfly throttle valve 29. Hence, this carbureter is constructed with the fuel chamber on top and so arranged that fuel will begin to flow through the nozzle 22 and down 90 through the carbureter the instant the slightest current of air enters the carbureting chamber 10. Were the positions reversed, fuel would not flow into the carbureting chamber at all until the motor had attained 95 a speed and power approximating that represented by at least 25% of its normal fuel load.

In the form shown in Fig. 3 the nozzle 22 in connection with the air inlet through the 100 passage 36 and the vortex producing carbureting chamber or snail shell like body 10 with tangential inlet 11 and axial mixture outlet 17 constitutes means for producing a moving column of air in the nozzle 22 105 and the hole 23 constitutes means to supply this particular column of air to the vortex producing and mixture producing means 10. The nozzle 22 and the surrounding reservoir with the float valve 33 and its connections constitute means for supplying the liquid fuel exteriorly to said moving column of air before it enters said mixture producing means or vortex forming chamber 10.

I claim:

1. In a carbureter having liquid supply means, a carbureting chamber below said liquid supply means, an air inlet into the carbureting chamber, an outlet passage opening from the mixing chamber below the level of the air inlet, a throttle valve for the outlet passage, a sump in the outlet passage, and a tube communicating with the sump and with the outlet passage beyond the throttle valve.

2. A carbureter comprising a liquid supply chamber; means to maintain liquid at a determined level in the supply chamber; a carbureting chamber located below said liquid supply chamber; an air inlet into the

carbureting chamber; a nozzle chamber communicating with the liquid in the supply chamber and with the air in the carbureting chamber and normally sealed from the air in the supply chamber; an air passage leading from said nozzle chamber to the air; and a valve to control said air passage.

3. A carbureter comprising a liquid supply chamber; means to maintain liquid at a determined level in the liquid supply chamber; a carbureting chamber below the liquid supply chamber; an air inlet opening into the carbureting chamber; a nozzle chamber communicating with the liquid in the liquid supply chamber and with the air in the carbureting chamber and normally sealed from the air in the liquid supply chamber; an air passage leading from said nozzle chamber to the air; and a valve and valve seat to control said air passage; said valve seat being provided with a minute groove to prevent absolute closure of said air passage.

4. A carbureter comprising a carbureting chamber having annular top and bottom ends; a liquid supply chamber and an outlet passage fitting said ends respectively and rotatable thereon and a connecting bolt and nuts adjustably fastening the chambers and passage together.

30 5. A carbureter comprising a carbureting chamber having annular top and bottom ends; a liquid supply chamber and an outlet passage fitting said ends respectively and rotatable thereon and a sectional connecting bolt and nuts adjustably fastening the chambers and passage together, a section of said bolt being chambered and there being a passage through the bolt from the liquid supply chamber into the carbureting chamber.

40 6. Apparatus for regulating the flow of liquid under varying suction comprising in combination a fuel chamber, means for maintaining fuel at a constant level in said chamber, a fuel supply pipe adapted to lead

the fuel from such chamber under such suction, downward, and of such size and free from such obstructions, as to permit the simultaneous passage of fuel and air therethrough and an internal chamber within the fuel chamber, inclosing the inlet to the said fuel supply pipe, and restricted air inlet at the top of said internal chamber communicating with the external air.

7. A carbureter having a throttle valve, and comprising a vortex mixing chamber 55 having a tangential air inlet and an axial mixture outlet, regulable means to supply liquid to said vortex mixing chamber and means to by-pass a portion of the supplied liquid past the throttle valve of the carbureter.

8. A carbureter having a throttle valve, and comprising a vortex mixing chamber having a tangential air inlet and axial outlet and means consisting of a fixed orifice for 65 supplying liquid to said vortex mixing chamber, and means to by-pass a portion of the supplied liquid around the throttle valve of the carbureter.

9. In a carbureter having liquid supply 70 means, a carbureting chamber below said liquid supply means, an air inlet into the carbureting chamber, an outlet passage opening from the carbureting chamber below the level of the air inlet, a throttle valve for the 75 outlet passage, a sump in the outlet passage, and a tube located wholly within the outlet passage and communicating with the sump and with a by-pass leading around the throttle valve.

In testimony whereof, I have hereunto set my hand at Los Angeles, California, this 13th day of November, 1912.

ORVILLE HIRAM ENSIGN.
